UNITED STATES PATENT OFFICE.

HENRY H. SLINGERLAND, OF RIVER FOREST, ILLINOIS.

BANJO.

Application filed October 29, 1924. Serial No. 746,607.

My invention relates to improvements in banjos, and it consists in the combinations, constructions, and arrangements herein described and claimed.

5 An object of my invention is to provide a banjo which is provided with novel means for causing the tone to have a clear, metallic ring, and which also has means for setting free the sound waves.

10 A further object of my invention is to provide a banjo which makes use of a special tension ring for tightening the membrane, this ring having an annular passageway around its entire surface, whereby the tension hooks may be readily adjusted to extend at right angles with respect to the hoop.

15 A further object of my invention is to provide a banjo which has a novel tone flange which is adapted to be set into vibration by the sound waves, and thereby lend a metallic ring to the notes of the banjo.

20 A further object of my invention is to provide a banjo in which the tone flange consists of a single piece and is constructed so as to be quickly assembled to the banjo.

25 A further object of my invention is to provide a banjo in which the entire membrane is supported by metal parts, thus aiding in giving the tones a metallic ring.

30 A further object of my invention is to provide a banjo in which the clamping rods are positioned below the top of the banjo where they will not obstruct the hands of the player.

35 Other objects and advantages will appear in the following specification, and the novel features of the invention will be particularly pointed out in the appended claims.

40 My invention is illustrated in the accompanying drawings forming part of this application, in which

45 Figure 1 is a plan view of my improved banjo,

Figure 2 is a plan view of the sound reflecting member,

Figure 3 is a section along the line 3—3 of Figure 1,

50 Figure 4 is an enlarged sectional view along the line 4—4 of Figure 6,

Figure 5 is a side elevation of Figure 4,

55 Figure 6 is a plan view of a portion of the device showing different parts of the banjo broken away to more clearly illustrate the construction of the banjo, and

Figure 7 is a section along the line 7—7 of Figure 2.

In carrying out my invention I provide a banjo which comprises a cylindrical wall 1 which is connected to a neck 2 by means of a strut 3. The strut 3 has a rounded end 4 which extends into a bore 5 in the neck 2, the rounded portion starting at a point adjacent to the inner surface of the wall 1. 60 As clearly shown in Figure 3, the rounded portion 4 extends through an opening 6 in the wall 1 and has its other end secured in place by means of a screw 7. The screw 7 extends through the wall 1 and into the strut 3 and is provided with a threaded bore 8 through which a bolt 9 extends. A nut 10 is adapted to draw the bolt 9 downwardly, whereby the bolt secures a tail-piece 11 in place. The tail-piece 11 supports the ends 70 of wires 12 in the ordinary manner. The wires 12 are strung over the bridge 13 and have their free ends secured to keys 14.

A sound reflecting member 15 is removably secured to the wall 1 by means of a bolt 16. In Figure 3 it will be noted that two plates 17 are disposed on the top and bottom of the strut 3 and are fastened in place by means of screws 18. The lowermost plate 17 has a threaded bore 19 therein 75 which receives the threaded end of the bolt 16. When the bolt 16 is screwed into the opening 19, it causes the sound reflecting member 15 to bear against the lower edge 20 of the circular wall 1. Supporting 80 pieces 21 are carried by the sound reflecting member 15 and bear against the edge 20. In this manner the member 15 is securely locked to the wall 1. It will be noted however, that the edge 20 is spaced above 85 the inner surface of the member 15 so as to provide a free passageway for the sound waves, whereby the sound waves are not obstructed in their passage from the instrument. 90

The sound waves are caused to flow past a tone flange 22 (see Figures 2 and 3). This flange is made of metal, and is in the shape of a split ring. A groove 23 is provided in the inner wall 24 of the member 15 and receives the flange 22. In Figure 7 I have shown how the free ends of the flange 22 are provided with downwardly extending strips 25. The ring is adapted to be contracted when being placed in position, and as soon as it is aligned with the groove 23 it will spring outwardly so as to enter the groove. 100 105 110

This movement causes the strips 25 to abut the inner surface 24. The screws 26 now secure the strip in place. It will therefore be seen that the tone flange or ring is locked 5 in place by means of the two screws 26 (see Figure 7). The flange 22 is provided with a plurality of circular recesses 27 which receive the lower ends of the clamping rods and lock nuts. The flange 22 substantially 10 fills the space between the wall 24 and the outer surface of the wall 1 (see Figure 3). It is therefore necessary that the sound waves pass the flange. The sound waves in 15 doing this, cause the flange to vibrate, the flange, in turn, lending a metallic ring to the notes.

I will now describe the novel manner of 20 securing the membrane 28 in place. This means is clearly shown in Figures 4, 5 and 25 6. In Figure 4 I have shown an enlarged sectional view through the membrane supporting member, and also have shown how the membrane is fastened in place. The tone ring 29 is provided with a flange 30 25 that is adapted to receive the cylindrical wall 1. The outer surface of the wall has an enlarged recess 31 which receives the flange 30. In this manner the outer surface of the wall 1 is made flush with the 30 outer surface of the flange 30. The ring 29 is also provided with an annular groove 32 in which a wire ring 33 is disposed. As clearly shown in Figure 4, the ring 29 is curved downwardly from a point adjacent 35 to the ring 33 and then extends in a substantially flat plane 34 toward the center of the banjo. An opening 35 is provided in the ring 29. The opening is large (see Figure 3) and permits all of the sound waves to 40 pass from the membrane 28 toward the reflector 15. I have found that by mounting the wire ring 33 upon metal tacks having rounded heads 36, the metallic ring of the sounds is greatly increased. I therefore 45 provide a plurality of these tacks and dispose them upon the upper edge 37 of the cylindrical wall 1. These tacks are spaced apart in the manner shown in Figure 6. The wire ring 33 rests upon these tacks and 50 therefore does not contact with the wood of the wall 1. As a further means of freeing the membrane from contact with wood I dispose a flange 38 upon the tone ring 29. In the present instance I have secured the flange 38 to the ring 29 by means of solder 55 39 spaced at intervals about the flange. The flange is spaced above the ring 29. The membrane is stretched across the flange 38 and contacts with the rounded portion 40 of the tone ring 29. From this point the membrane is passed downwardly and is wrapped around a skin hoop 41 and then 60 up between a tension ring 42 and the outer surface of the wall 1.

65 One of the novel features of the device

lies in the fact that the tension ring 42 is provided with an annular passage 43 which is V-shaped at 44 so as to receive the J-shaped ends 45 of the tension hooks 46. The groove 43 permits the hooks to be moved laterally so as to dispose the hooks in a vertical position and still permit the hooks to be aligned with brackets 47. The brackets 47 are fastened in place to the cylindrical wall 1 by means of bolts 48 which are passed through openings 49 in the wall. Lock nuts 50 are screwed upon the lower ends of the hooks 46 and when tightened cause the hooks to pull downwardly on the tension ring 42 and thus place the membrane 28 under the 70 required tension. By this means I am enabled to place the membrane 28 under approximately 2700 pounds pressure. It will be noted from Figure 4 that when the membrane 28 is tightened, it is held entirely free 75 of all wooden parts. The membrane contacts the flange 38, the rounded portion 40, the flange 30, and the tension ring 42. It will therefore be noted that the tops of the tension hooks 46 do not extend above the upper edge of the tensioning ring, as is the construction in standard banjos. This provides an even surface to the top of the banjo, and obviates any tendency of the hands of the banjo player to strike these projections. 80 Furthermore, the tension ring is not provided with notches to receive the tops of the hooks 46, as is the usual practice. The hooks 46 on the other hand, may be moved to any 85 point along the groove 43 so as to permit the hooks to be aligned with the brackets 47. 90

95 From the foregoing description of the various parts of the device, the operation thereof may be readily understood. There are three features which are novel in the 100 present invention. The first is the provision of the tone flange 22. The second is the provision of the means of supporting the membrane by metal parts, and the third is the 105 novel construction of the tension hooks. I have clearly described in the specification, how the tone flange 22 may be quickly applied to the sound reflecting member 15, and secured in place by means of the screws 26. I have also shown how the tone ring 29 is 110 supported by metal tacks, thus causing the tones emitted from the banjo to have a metallic ring. The third novel point lies in the special construction of the tension hooks 46. The hooks have their upper ends received in a V-shaped groove which relieves 115 any lateral strain upon the hooks when they are in place. This is a distinct feature of the present invention. The entire banjo has been especially designed to free all of the 120 sound waves and to give a clear, metallic ring to the notes.

I claim:

1. In a device of the type described, a cylindrical wall, a metal supporting member 130

- adapted to support a membrane carried by said wall and having an opening therein, a flange carried by said supporting member and bearing against the membrane, said flange extending outwardly away from said supporting member throughout the greater portion of its width. 20
2. In a device of the type described, a cylindrical wall, a metal supporting member adapted to support a membrane carried by said wall and having an opening therein, a flange carried by said supporting member and bearing against the membrane, said flange extending outwardly away from said supporting member throughout the greater portion of its width, the part of the flange contacting with the membrane being curved so as to tangentially contact with the membrane. 25
3. A device of the type described comprising a cylindrical wall, a sound-reflecting member, means for securing said sound-reflecting member to said wall and for spacing the sound-reflecting member from said wall, and a tone flange secured to said sound-reflecting member, the inner edge of said flange being spaced a slight distance from the outer surface of said cylindrical wall. 25

HENRY H. SLINGERLAND.
